UNITED STATES PATENT OFFICE.

FRANK J. GRESSLY, OF NEW YORK, N. Y.

DESIGN FOR A MATCH-BOX HOLDER.

SPECIFICATION forming part of Design No. 32,734, dated May 29, 1900.

Application filed May 4, 1900. Serial No. 15,543. Term of patent 7 years.

To all whom it may concern:

Be it known that I, FRANK J. GRESSLY, a citizen of the United States, residing at the city of New York, (Brooklyn,) county of Kings, 5 and State of New York, have invented and produced a new and original Design for Match-Box Holders, of which the following is a specification.

My invention relates to a new and original 10 design for match-box holders and similar articles; and it consists in the configuration and ornamentation substantially as shown in the accompanying drawings, forming part of this specification, in which—

15 Figure 1 is a side elevation, and Fig. 2 an end view.

The article comprises two sides A A and a bottom piece B. Generally the form of the article *per se* is conventional, except that the 20 side pieces are given a new shape in outline, substantially as shown. The exterior sur-

face of the side pieces A A are ornamented in relief by producing the cherubic figures 1, 2, and 3 thereon, a plain panel 4 being produced between the figures 1 and 2. The edge 25 of the parts A A are ornamented by the floral-work 5, the figures 1 2, and crown-piece 6, the figures 1 2 and floral-work 5 being connected by the bars 7. The ground of the parts A has a stippled effect. 30

I claim—

The design for a match-box holder, or similar article, substantially as herein shown and described.

Signed at the city of New York, (Brooklyn,) 35 county of Kings, and State of New York, this 12th day of April, 1900.

FRANK J. GRESSLY.
